DESIGN FOR A FLAG HOLDER OR SIMILAR ARTICLE

Edward E. Farley and Kenneth A. Bird,
Pocatello, Idaho

Application March 5, 1943, Serial No. 109,680

Term of patent 7 years

To all whom it may concern:

Be it known that we, Edward E. Farley and Kenneth A. Bird, citizens of the United States of America, residing at Pocatello, county of Bannock, and State of Idaho, have invented a new, original, and ornamental Design for a Flag Holder or Similar Article, of which the following is a specification, reference being had to the accompanying drawings, forming a part thereof wherein:

We claim:

The ornamental design for a flag holder or similar article, as shown.

EDWARD E. FARLEY.
KENNETH A. BIRD.
